UNITED STATES PATENT OFFICE.

JOSEPH N. FOUNTAIN, OF WESTFIELD, MASSACHUSETTS, ASSIGNOR TO OLD COLONY ENVELOPE COMPANY, OF WESTFIELD, MASSACHUSETTS, A CORPORATION OF MASSACHUSETTS.

DECKLING MACHINE.

Application filed August 19, 1925. Serial No. 51,256.

This invention relates to improvements in machines for shaping the edges of material and relates more particularly to machines for deckling the edges of such material as 5 paper, card, bristol board, or the like.

It is common practice to deckle the edges of paper during the manufacture thereof but this entails considerable expense in the manufacturing cost and tends to retard the speed 10 of production of the paper. Finished paper has also been deckled by various means, more particularly, as by a grinding wheel but this method is objectionable since the grinding action tends to rapidly wear the wheel which 15 then ceases to give the desired deckled appearance that corresponds to the deckle produced in the manufacture of the paper.

According to my invention I am able to produce the desired results by the provision 20 of rotary cutting tools of novel form that are so disposed with respect to the edge of the paper that they act upon the paper with a shearing cut and tend, during the cutting action, to exert a pulling strain upon the 25 paper in opposite directions.

I have found that various grades or kinds 30 of paper require different deckled effects and according to one feature of the invention, I have provided a cutting tool holder that is adjustable so that according to the tool employed, it may be adjusted to position the 35 axis of the tool so that it will operate on the paper with the desired shearing and pulling action.

Other novel features will be apparent 40 from the following description of the invention which, in the form at present preferred, is illustrated by means of the accompanying drawings in which:

Fig. 1 is a plan view of the machine;

Fig. 2 is a sectional elevational view taken on the line 2—2 of Fig. 1, showing the cutting tool holder and driving means therefor and;

Fig. 3 is a sectional elevational view taken on the line 3—3 of Fig. 1, showing the cutting tool and support for the web of paper.

In describing the novel features of my invention, it will be understood that the machine may be adapted for use with other material than paper or cardboard and that any reference to such material is only intended to assist in an explanation and an understanding of the structure.

A table 1 for supporting a web of material such as paper, is provided that is in the form of a flat plate member secured to and supported by standards or legs 2. Guides 3, for guiding a web of paper through the machine, preferably consist of flat plates disposed in a vertical position and are guided on the table by tongues or slides 4 fitting between guideways 5 secured to the table. These guides are movable towards and away from one another and are held in various 60 positions of adjustment by clamping screws 6. The standards or legs 2 are held in a rigid spaced relation by suitable tie rods 7 and preferably extend forwardly of the supporting plate and have secured thereto cross bars 7' on which are fixed a plurality of spaced bars 8 and side guides 8' which form a receiving table for the sheets as they are fed from the feed table and through the deckling mechanism soon to be described. 70 This table may, of course, take any form desired and is preferably arranged to incline 75 downwardly from the table 1.

Shafts 9 and 9', rotatable in suitable bearings 10 of the supports 2, have fixed thereon 80 coacting feed rolls 11 and intermeshing gears 12. The shaft 9' is provided with a driving pulley 13 whereby a rotary motion, imparted to the pulley, will cause the rolls to operate in unison to grip therebetween a sheet or 85 web of paper and feed it forwardly through the deckling mechanism and onto the delivery table. The pulley 13 may be driven from any suitable source of power and at any speed desired or it may be belted to any of 90 the well known variable speed driving devices so that the speed may be varied from time to time.

A rod 14 extends across the table which is supported in brackets 15 and carries a plurality of friction devices, preferably in the form of brushes 16, which are adapted to bear upon the paper as it is fed forwardly by the feed rolls 11 and tends to maintain 95 the paper in a flat condition. Guide members 17 fixed to the rod 14 extend forwardly thereof and have their forward ends disposed beneath other guides 18 fixed to the guides 3. These guides are preferably arranged to guide the paper as it is fed forwardly and to prevent it buckling when 100 acted upon by the cutting mechanism.

Supporting plates 20 are secured at either

side of the table to the supports 2 and carry a standard 21 which has slidably mounted therein a post 22 of a tool holder 23. The standard is preferably split axially thereof and is provided with a clamping screw 24 for binding the post 22 therein in various positions of adjustment. As will be seen, the holder 23 may be rotated to any position desired and clamped therein.

10 An adjusting screw 25 having a thrust collar 26 held from axial displacement by the plate 20 and standard 21, has its upper end in screw threaded engagement with the post 22 by the means of which the tool holder may be raised or lowered to various positions of adjustment. An index dial 28 fixed on the screw carries designating markings which may be registered with a pointer 29 located in an opening 30 in the side of the standard by the means of which, settings of the holder may be duplicated as may be desired.

15 The holder 23 has a shaft 24' rotatable therein that is provided with a tool holding chuck 25' of usual form at its forward end and a driving pinion 26 fixed to its rearward end. A motor M atop of the holder has a driving gear 27 fixed to the shaft thereof that is in meshing engagement with the pinion 26 for driving the shaft 24'.

20 A tool T preferably in the form of a milling cutter having peripheral cutting teeth disposed longitudinally thereof, is clamped in the chuck 25' and is preferably disposed so as to overlie a paper supporting member 29' that is carried by an arm 30' extending upwardly from the standard 21. This member 29' is arranged to engage the underside of the paper to support the same against the 25 action of the cutter and may take any form desired, that shown being a disc that is secured to the arm by a screw 31. It is not necessarily rotatable on the screw 31 but may be fixed rigidly and moved about its axis to present new supporting surfaces should the tool cut or injure it.

25 The cutting teeth of the cutting tool may take any of the usual forms, that shown being of the spiral type which has been found preferable for certain kinds of paper, while straight teeth or nearly so, may be more advantageously employed for other kinds.

30 As will be noted, the tool holder may be adjusted vertically to accommodate different thicknesses of paper or to create various deckle effects and that it is rotatable so that according to the type of tool employed, the tool may be disposed at various angles with respect to the edges of the paper whereby it 35 will operate thereagainst with a shearing action as is desirable to produce the most perfect deckle edge effect.

35 Regardless of the particular form of cutting tools employed, it is possible to so position them with respect to the edge of the

paper that their cutting teeth will, when operating on the paper, exert a pulling action,—that is, while the cutters are acting upon opposite edges of the paper they will also tend to pull the paper in opposite directions to flatten the paper for the shearing cut and thereby assist the cutting operation so that the finest possible cuts may be made to produce the desired fine quality deckle edge.

40 I am aware that many changes may be made in the form of the invention without departing from the scope thereof, and I prefer, if at all, to be limited by the following claims rather than by the foregoing description.

What I claim is:

1. In a machine of the class described in combination, a table and a guide for supporting and guiding a web of material, a rotary cutting tool to operate upon one side of said web having its axis of rotation disposed in a plane substantially parallel to that of said web and being adapted for adjustment so that its axis of rotation may be disposed at various angles with respect to the edge of said web.

2. In a machine of the class described in combination, a table for supporting a web of material, a rotary cutting tool for operating on a portion of said web disposed to have its axis of rotation substantially parallel with said portion of the web and arranged to operate upon one side of said web and means for adjusting said tool so that its axis may be positioned at various angles with respect to the edge of said web.

3. In a machine of the class described in combination, a table and a guide for supporting and guiding a web of material, a rotary cutting tool disposed to operate upon one side of said web and being adapted for adjustment so that its axis of rotation may be disposed at various angles but in planes substantially parallel with respect to the edge of said web, and means for adjusting the tool transversely of its axis.

4. In a machine of the class described, in combination, a table for supporting a web of material including a guide therefor, a rotary cutter disposed above said web arranged to have its axis substantially parallel with said web therebelow and adapted to operate upon one side of said web at the edge thereof with a shearing action, means for adjusting said tool so that its axis of rotation may be positioned at various angles with respect to the edge of said web, and a member underlying said web and engaging the other side thereof for supporting said web against the shearing action.

5. In a machine of the class described in combination, a table for supporting a web of material including a guide therefor, a rotary cutter disposed above said web with

its axis substantially parallel with the plane of said web therebelow arranged to operate upon one side of said web at the edge thereof with a shearing action, means for adjusting said tool so that its axis of rotation may be positioned at various angles with respect to the edge of said web, and a member underlying said web and engaging the other side thereof for supporting said web against the shearing action, and means for adjusting the tool transversely of its axis so that it may be positioned at various distances from said member.

6. In a machine of the class described in combination, a table for supporting a web of material including a guide therefor, means for feeding a web of material along said table, rotary cutting tools disposed on one side of said web having spiral cutting teeth for operating upon said web at opposite edges thereof with a shearing action and adapted to exert a pulling force upon said web in opposite directions.

7. In a machine of the class described in combination, a table for supporting a web of material including a guide therefor, means for feeding a web of material along said table, rotary cutting tools disposed on one side of said web having spiral cutting teeth for operating upon said web at opposite edges thereof with a shearing action and adapted to exert a pulling force upon said web in opposite directions, the said tools being adjustable so that their axis of rotation may be positioned at various angles with respect to the edges of the web.

8. In a machine of the class described in combination, a support for a web of material, a tool holder movable in planes substantially parallel and transversely thereto, a cutting tool rotatable in said holder having peripheral cutting teeth adapted to operate on a side of said web with a shearing action, and a member for engaging the other side of said web to support the same for the action of the tool.

9. In a machine of the class described in combination, a support for a web of material, tool holders disposed at opposite sides

of said support that are movable in planes substantially parallel and transversely thereto, cutting tools rotatable in said holders having peripheral cutting teeth adapted to operate upon one side of said web at opposite edges thereof with a shearing action and adapted to exert a pulling action on said web in opposite directions, and members for engaging the other side of said web to support the same for the action of the tool.

10. In a machine of the class described in combination, a support for a web of material including guides therefor, a tool holder at opposite sides of said support that are independently movable in planes substantially parallel and transversely thereto, means for feeding a web along said support, cutting tools rotatable in said holders having peripheral cutting teeth for operating upon one side of said web with a shearing action and adapted to exert a pulling action upon said web in opposite directions, members for engaging the other side of said web to support the same for the action of the cutters.

11. In a machine of the class described in combination, a support for a web of material, a rotary cutter disposed to have its axis substantially parallel with said web and at an angle with the edge thereof and provided with peripheral cutting teeth extending substantially longitudinally thereof adapted to operate upon a side of said web with a shearing action.

12. In a machine of the class described in combination, a support for a web of material, a rotary cutter disposed to have its axis substantially parallel with said web and at an angle with the edge thereof and provided with peripheral cutting teeth extending substantially longitudinally thereof adapted to operate upon a side of said web with a shearing action, and a member for engaging the other side of said web to support the same against the action of the cutter.

In testimony whereof I have affixed my signature.

JOSEPH N. FOUNTAIN.
